UNITED STATES PATENT OFFICE.

HARRY W. LASTER, OF CHICAGO, ILLINOIS, ASSIGNOR TO THE BARBER ASPHALT PAVING COMPANY, OF WASHINGTON, DISTRICT OF COLUMBIA, AND NEW YORK, N. Y., A CORPORATION OF WEST VIRGINIA.

APPARATUS FOR CONSTRUCTING ASPHALT PAVEMENTS.

SPECIFICATION forming part of Letters Patent No. 727,160, dated May 5, 1903.

Application filed December 15, 1902. Serial No. 135,188. (No model.)

To all whom it may concern:

Be it known that I, HARRY W. LASTER, of Chicago, in the county of Cook and State of Illinois, have invented certain new and useful Improvements in Apparatus for Constructing Asphalt Pavements; and I do hereby declare that the following is a full, clear, and exact description thereof, reference being had to the accompanying drawings, and to the letters of reference marked thereon, which form a part of this specification.

This invention relates to apparatus for making asphalt pavements, and refers more specifically to a device for applying the binder to the foundation of such a pavement by which the asphalt wearing-surface is cemented or bound to the foundation.

Conveniently my improved apparatus is attached to a steam packing-roller of ordinary type, whereby after the foundation has been properly packed the roller is again passed over said foundation and the binder in a melted or fluid state is discharged upon the foundation preparatory to applying the asphalt wearing-surface thereto. Said binder applying apparatus may, however, be applied to or made a part of any other suitable vehicle.

The invention consists of the matters hereinafter set forth, and more particularly pointed out in the appended claims.

In the drawings, Figure 1 is a fragmentary side view of a steam-roller, showing the manner of applying my invention thereto. Fig. 2 is a vertical transverse section of the device for applying the binder. Fig. 3 is a top plan view, with parts removed and other parts broken away, of said device. Fig. 4 is a plan view taken on line 4-4 of Fig. 2. Fig. 5 is a detail of the pipes for delivering steam to the heating-chamber. Fig. 6 is a detail of means for operating the discharge-nozzle of the device and also the valve of said pipe. Fig. 7 is a vertical section taken in a plane at right angles to that of Fig. 2. Fig. 8 is a fragmentary rear end view of a steam-roller, showing a modified form of the device mounted thereon.

As shown in said drawings, A designates as a whole a steam-roller of familiar con-

struction embracing a traction and packing 50 roller A', which is rotatively mounted in bearings on the frame members A².

B designates the usual boiler supported on the frame in front of said roller, and B' an engine supported on the frame A² and geared 55 to the roller A' in a manner to give motion to the same in a familiar manner.

A device embodying my invention for applying the binder to the foundation of the pavement embraces a heating box or chamber C, which is shown in Fig. 1 as supported from the rear end of the roller-frame by means of arms A³, extending rearwardly from said frame and attached to the heating-chamber near the lower end thereof, and tension-rods A⁴, attached to the upper side of said frame and connected at their lower ends with eyes c, which are attached to the upper part of the chamber. Said heating-chamber is herein shown as made rectangular and is provided with a removable top or cover made in two sections C', and the bottom wall of said chamber is permanently connected with the side walls thereof. Said chamber is provided at its upper end near one side with a hopper C⁴, 75 through which the binding material in a semi-fluid state is fed to the chamber. Contained within the chamber is a heating-coil D, located near the chamber-walls and through which steam is adapted to be passed to maintain the binder material in a fluid or melted state. The upper end of the coil is connected with a steam-header D', located at the upper end of the chamber, which header is connected by a pipe E with the boiler, whereby live steam 85 is supplied to the coil. Said pipe E is provided with cut-off valves e e'. The coil D communicates at its lower end with a horizontal coil D², located at the lower end of the heating-chamber, and said coil D² terminates 90 in an exhaust-pipe D³, which extends downwardly through the lower wall thereof centrally of and at the front part of said chamber.

F designates a discharge-pipe for the chamber, through which the binder in a liquid form 95 is discharged upon the pavement-foundation, said pipe communicating with a central opening in the lower wall of the chamber and ex-

tending rearwardly and is provided at its rear end with a discharge-nozzle F', which is preferably made of flaring or fan shape in plan view, as shown in Fig. 3, and is provided 5 with a horizontally elongated restricted discharge opening or slit. Said nozzle is shown as having screw-threaded engagement with the discharge-pipe F, whereby the angular position of the nozzle upon the pipe may be 10 varied. The pipe has loose or swiveling connection with a part on the lower wall of the tank, whereby its rear end may be swung laterally to cover an extended area of the pavement-foundation. The rear end of the 15 pipe is guided between upper and lower guides F² F³, extending from hangers F⁴, depending from a platform C⁵, extending rearwardly from the bottom wall of the chamber by means of tension-rods C⁶, as shown in Fig. 20 2. Said platform C⁵ serves as a support upon which the operator may stand to direct the several movements of the apparatus. The flow or discharge of the liquid binder from the chamber to the pipe F is controlled by a 25 rotative valve G, contained in a tube or sleeve, which constitutes a continuation of the discharge-pipe F and extends upwardly through the discharge-opening in the bottom of the heating-chamber and has rotation in 30 said bottom. Said discharge-pipe is connected with the lower end of the tube or sleeve G' by means of an elbow f. Said tube or sleeve and the hollow valve are provided with registering ports. The tube or sleeve 35 G' is surrounded by a packing-gland consisting of a metal packing-ring H, surrounding the tube and fitting against the bottom wall of the chamber, and a washer H', located beneath said packing-ring, and the washer 40 and the ring are affixed to said bottom wall of the chamber by means of bolts h, extending therethrough and through the bottom wall of the chamber, as more clearly shown in Fig. 2. In order to hold the tube or sleeve 45 G', vertically stationary while permitting it to rotate, said sleeve is provided with an annular flange g, which fits between the packing-ring and the bottom wall of the box, and the contacting faces of said flange and packing-ring are correspondingly tapered. The pipe F is given a swinging movement through the medium of a hollow shaft I, which extends upwardly through the heating-chamber and has rotative bearing at the upper 50 end thereof in a transverse bar C⁷, attached to the side walls of the chamber and located between the cover-section C', as shown in Figs. 3 and 4. Said shaft is provided at its upper end with a manually-operable part, such as the hand-wheel I', through which 55 rotary motion is imparted to said shaft to horizontally swing said delivery-tube F.

The valve G is actuated to open and close the same through the medium of a valve-stem G², affixed to the valve and extending upwardly through the hollow shaft I and

through the hub of the hand-wheel I', and is provided at its upper end with an operating-lever G³, through which power is applied to rotate the valve to open and close the same. 70 Said hand-lever is provided with a spring-actuated latch g², (shown more clearly in Fig. 6,) which is adapted to seat in a series of notches in the upper face of the rim of the hand-wheel I', whereby the valve is held 75 positively in its open and closed positions or any intermediate position. With this construction it will be noted that when the valve is opened the shaft I' may be rotated in its bearing to swing the discharge-pipe F through 80 the arc of its travel and that the valve G rotates with said shaft and the tube or sleeve G', whereby the position of the valve with respect to the said tube is not disturbed by the rotation of the shaft and the swinging of 85 the discharge-pipe F.

The melted or fluid binder is discharged through the pipe F through the ejection action of steam or like fluid under pressure, which is introduced to the nozzle F'. Said 90 ejecting fluid may consist of the exhaust-steam from the heating-coil D, or live steam may be introduced to said nozzle for the purpose of forcing the liquid binding therefrom. As herein shown, the nozzle is adapted to receive both the live and exhaust steam, and the parts are so arranged that both live and exhaust steam may be employed or the exhaust-steam separately. For this purpose the exhaust-pipe D⁸, leading from the lower coil D² 95 in the heating-chamber, is connected, by means of a flexible hose or pipe J, with a branch F⁵, made integral with the nozzle F' and provided with a passage which communicates with the outlet slit or passage of the 100 nozzle F' at a proper angle to produce the desired ejecting action of the steam upon the liquid binder to discharge the same through the nozzle. The live-steam pipe E is also connected with said exhaust-pipe D⁸ by means 105 of a branch pipe E', provided with a cut-off valve e². The combined use of the exhaust and live steam is desirable when using the apparatus in cold weather, for the reason that at such times the fluid binder material in 110 passing through the pipe F is exposed to a low temperature and becomes thickened and requires a greater ejecting force to discharge it from the nozzle F' than when in a thinner or more completely fluid state. Moreover, 115 the introduction of the live steam to the exhaust-pipe D⁸ equalizes the steam-pressure in the upper and lower parts of the coil and increases the heating effect of the steam in the chamber. 120

The discharge-nozzle F' is shown as provided with a handle F⁶, by which the discharge-slit of the nozzle may be turned angularly, so as to control the sheet of fluid binder material discharged therefrom under 125 all conditions of lateral air-currents which may have an influence on the discharging

material to spread it unevenly on the pavement-foundation to which it is applied.

The heating-chamber is shown as provided with two vertical partitions K K, which are attached to the top wall-sections thereof and are seated at their lower ends in suitable guides K' K' on the floor of said chamber. Said partitions divide the chamber into communicating compartments and tend to prevent the vibration of the vehicle to which the device is attached from splashing the liquid binding material out of the chamber through the hopper thereof.

In Fig. 7 I have shown the heating-chamber of my improved apparatus as being supported on the top of the roller-frame at the rear end thereof. As shown in said figure, L designates the heating-chamber, and L' the filling-hopper thereof. M designates a steam-pipe leading from the boiler and connected with the upper part of the steam-coil in the chamber L through the medium of a valved branch pipe M'. The liquefied binding material is discharged from the heating-chamber through the medium of a flexible pipe N, which leads from the bottom wall of said chamber near the rear end thereof. Said pipe N extends downwardly from said chamber and is adapted to drag behind the roller upon the pavement-foundation and is provided at its rear end with a discharge-nozzle N', made substantially like the discharge-nozzle F' of the construction heretofore described. Said discharge-nozzle is connected with the exhaust-pipe O of the coil in the chamber L through the medium of a connection-pipe O', the rear end of said pipe O' being connected with a branch N² of said discharge-nozzle in the same manner as is the flexible pipe J connected with the nozzle F' of the previously-described construction. Said exhaust-pipe O is also connected with the live-steam pipe M through the medium of a valved branch pipe M², whereby both live and exhaust steam may be supplied to said nozzle. The pipe N, through which the fluid binder material is discharged, is provided near the heating-chamber L with a valve N³, by which the flow of material through said pipe is controlled. The nozzle N' is provided with a handle P, by which it may be manipulated to spread the material over the pavement-foundation, and said handle is provided at its lower part with one or more rollers P', which are adapted to support the weight of the nozzle. The pipes O' and N are preferably wire-wound, so as to withstand the wear occasioned by the dragging of said pipe on the pavement-foundation.

An important advantage gained by the use of the apparatus herein shown is that fluid binder material may be spread evenly and uniformly over the pavement-foundation, and by reason of the regulating-valves located in the pipe through which the binding material is discharged from the heating-chamber the

thickness or layer of the binding material laid upon the pavement-foundation may be varied as desired.

Another important advantage gained by the use of my apparatus is that the binder material may be spread upon the pavement-foundation much more rapidly and with greater economy than under the present prevailing practice, which consists of pouring the material upon the pavement-foundation from vessels of relatively small capacity having suitable spouts through which the material is discharged upon the foundation, said vessels being carried from heating or melting pots or tanks by attendants to the places where the material is to be applied. With the use of my apparatus I am enabled to dispense with the services of all but one person heretofore required for laying or spreading said binder material. As before stated, the mounting of said apparatus upon the steam-roller commonly employed for packing the pavement-foundation is a convenient arrangement; but it will be understood that said apparatus may be supported and conveyed from place to place upon any other suitable vehicle provided with the necessary heating devices for keeping the binder material in a fluid state and forcing devices for discharging the fluid from the heating-chamber to the pavement-foundation. It is to be understood, furthermore, that various changes may be made in the structural details and the arrangement of the parts without departing from the spirit of my invention, and I do not wish to be limited to the details shown except as hereinafter made the subject of specific claims.

I claim as my invention—

1. An apparatus for the purpose set forth comprising, in combination with a suitable vehicle, a heating-chamber for the binder material, means for heating said chamber, a horizontally-swinging discharge-pipe leading from said chamber and provided with a nozzle having a narrow, generally horizontal discharge-orifice, means for swinging said discharge-pipe horizontally at the time the binder material is being discharged therefrom, and means for applying a fluid under pressure for forcibly discharging said binder material through said pipe and nozzle.

2. An apparatus for the purpose set forth comprising, in combination with a suitable vehicle and a steam-generator carried thereby, a heating-chamber for the binder material, a heating device in said chamber which receives steam from the generator, a horizontally-swinging discharge-pipe for said chamber provided with a discharge-nozzle, and means for delivering steam under pressure from said generator to forcibly discharge the binder material through said pipe and nozzle.

3. An apparatus for use in constructing asphalt pavements comprising, in combination with a suitable vehicle and a steam-generator carried thereby, a heating-chamber, a steam

heating device in said chamber which receives steam from said generator, a discharge-pipe for said chamber provided with a nozzle and a pipe for delivering steam under pressure to said nozzle.

4. An apparatus for use in constructing asphalt pavements comprising, in combination with a suitable vehicle and a steam-generator carried thereby, a heating-chamber, a steam heating device in said chamber which receives steam from said generator, a discharge-pipe for said chamber provided with a nozzle, and a pipe leading from the exhaust end of said heating device to said nozzle.

15 5. An apparatus for use in constructing asphalt pavements comprising, in combination with a suitable vehicle and a steam-generator carried thereby, a heating-chamber, a steam heating device in said chamber which receives steam from said generator, a discharge-pipe for said chamber provided with a nozzle, a pipe leading from the exhaust end of said heating device to said nozzle, and a steam-pipe leading from the generator and discharging through said nozzle.

6. An apparatus for use in constructing asphalt pavements comprising, in combination with a suitable vehicle, a heating-chamber for the binder material, a steam heating device in said chamber, means for supplying steam thereto, a discharge-pipe for said chamber provided with a nozzle having a restricted, generally horizontal, discharge-opening, and a steam-pipe for delivering steam under pressure to said nozzle.

7. An apparatus for use in constructing asphalt pavements comprising, in combination with a suitable vehicle, a heating-chamber for the binder material, a discharge-pipe provided with a nozzle having a narrow, generally horizontal, discharge-opening, means for forcibly discharging the binder material through said nozzle, and means for varying the angular position of said nozzle upon said pipe.

45 8. An apparatus for use in constructing asphalt pavements comprising, in combination with a steam-roller, a steam-generator, and an engine which receives steam from said generator and geared to the traction-roller to operate the same, a heating-chamber, a heating device in said chamber which receives steam from said generator, a discharge-pipe for said chamber provided with a nozzle, and a pipe for delivering steam under pressure to said nozzle.

9. An apparatus for use in constructing asphalt pavements comprising, in combination with a steam-roller, a steam-generator, and an engine which receives steam from said generator, and is geared to the traction-roller to operate the same, a heating-chamber, a heating device in said chamber which receives steam from said generator, a horizontally-swinging discharge-pipe for said chamber provided with a nozzle having a slotted discharge-

opening, and a pipe for delivering steam under pressure to said nozzle.

10. An apparatus for use in constructing asphalt pavements comprising, in combination with a steam-roller provided with a steam-generator and engine which receives steam from said generator and is geared to the traction-roller to operate the same, a heating-chamber, a heating device in said chamber which receives steam from said generator, a discharge-pipe for said chamber provided with a nozzle, a pipe connecting the exhaust end of the heating device with said nozzle and a pipe leading from said generator to the exhaust-steam pipe and provided with a valve. 70

11. An apparatus for use in constructing asphalt pavements comprising, in combination with a suitable vehicle and a steam-generator carried thereby, a heating-chamber for the binder material, a heating device in said chamber which receives heat from the generator, a discharge-pipe for said chamber provided with a nozzle, means for delivering steam under pressure to said nozzle, means for swinging said discharge end of the nozzle 85 and a valve for controlling the passage of the binder material through said pipe.

12. An apparatus for use in constructing asphalt pavements comprising, in combination with a suitable vehicle, a heating-chamber 95 for the binder material, a horizontally-swinging discharge-pipe for said chamber provided with a nozzle, a pipe for delivering a fluid under pressure to said nozzle, a rotative shaft connected with said discharge-pipe for 100 swinging the same and provided with a hand-wheel or like device for rotating the shaft, a valve for controlling the passage of the binder material through said discharge-pipe and adapted to rotate with said shaft, a valve-stem 105 connected with and operating said valve, a lever for rotating said valve-stem and means for locking said valve-stem lever to the said hand-wheel.

13. An apparatus for use in constructing 110 asphalt pavements comprising, in combination with a suitable vehicle, a heating-chamber for the binder material, a horizontally-swinging discharge-pipe for said chamber provided with a nozzle, a pipe for delivering a 115 fluid under pressure to said nozzle, a hollow rotative shaft connected with said discharge-pipe for swinging the same, and provided with a hand-wheel or the like for rotating said shaft, a valve for controlling the passage of 120 the binder material through said pipe and adapted to rotate with said shaft, a valve-stem connected with said valve and extending upwardly through said hollow shaft, a lever for rotating said valve-stem, and means 125 for locking said lever to said hand-wheel.

14. An apparatus for use in constructing asphalt pavements comprising, in combination with a suitable vehicle, and a steam-generator carried thereby, a heating-chamber, a 130

steam heating device for said chamber which receives steam from said generator, a discharge-pipe for the heating-chamber provided with a nozzle, a steam-pipe for delivering steam to said nozzle, and one or more partitions in said chamber dividing the same into a plurality of compartments communicating with each other at the bottom of the chamber.

In testimony that I claim the foregoing as my invention I affix my signature, in presence of two witnesses, this 8th day of December, A. D. 1902.

HARRY W. LASTER.
